UNITED STATES PATENT OFFICE.

JACOB STOCKE, JR., OF ST. LOUIS, MISSOURI, ASSIGNOR TO PROGRESS PRESS BRICK AND MACHINE COMPANY, OF ST. LOUIS, MISSOURI, A CORPORATION OF MISSOURI.

BRICK-SURFACING MACHINE.

Application filed March 11, 1922. Serial No. 542,991.

To all whom it may concern:

Be it known that I, JACOB STOCKE, Jr., a citizen of the United States, and resident of the city of St. Louis and State of Missouri, have invented certain new and useful improvements in Brick-Surfacing Machines, of which the following is a specification containing a full, clear, and exact description, reference being had to the accompanying drawings, forming a part hereof.

My invention relates to improvements in brick surfacing machines, and has for its object a brick surfacing machine which is provided with an automatically operated device for scoring or surfacing one side and both ends of a brick simultaneously, so as to produce what is known as a "mat brick", and which can be readily attached and detached to any of the power presses now in use.

In the drawings,

Fig. 1 is a front elevation of a brick press with my device attached thereto.

Fig. 2 is a side elevation of a brick press with my device in position.

Fig. 3 is a top plan view of a brick press with the ram and end scoring mechanism removed.

Fig. 4 is an enlarged vertical cross section taken through the central guiding strip and scoring cutters.

Fig. 5 is an enlarged fragmental perspective view, showing one end of the end scoring mechanism.

Fig. 6 is a fragmental view of one surface of a brick, showing the same partially scored by my device.

In the construction of my device I employ a brick press which is of ordinary construction and comprising a frame which is provided with integrally formed vertical slides or guide ways 7 in which is slidably mounted the ram 8. This ram is operated by means of a lever 9. Secured to the lower end of the ram 8 are plungers 10 which fit into the moulds 11 formed in the table 12 of the press. Slidably mounted on the table 12 is a plunger 13 which is provided with a recess 14. This plunger not only removes the brick after having been pressed but the recess 14 becomes filled with clay charges the moulds, so that the removing of the finished brick and charging of the mould is done in one operation.

Secured to the front of the press is a table 15 to which smooth guiding strips 16 are secured, and a central guiding strip 17. This central guiding strip is provided with vertical recesses 18, and positioned in these recesses and extending through the strip 17 are the scoring cutters which have cutting edges 19, and a threaded portion 20, so that the same can be secured within the strip 17. The table 15 is provided with openings 21 which are in alinement with the vertical recesses 18 and which permit the material removed from the bricks to pass therethrough, so as to leave the table clear at all times for the passage of bricks between the strips. Secured to the table 15 are U-shaped frames 22 which are connected together at their upper edges by bars 23. Mounted on each of the frames 22 is a bearing 24 through which a shaft 25 passes. Each pair of legs of the U-shaped frame 22 have extending therethrough a rod or shaft 26. This rod or shaft acting as a guide for the cutter frames 27. Each cutter frame is also U-shaped and is adapted to straddle the strips 16 and 17. The U-shaped frames are connected together by tie-bars 28 which have extending therethrough a shaft 29. This shaft is straddled by the forked end 30 of the operating lever 31. The operating lever is secured to the shaft 25. Its upper end 32 is curved and is designed to pass between the rollers 33 and 34. The roller 33 is pivotally secured in a bearing block 35, which block is in turn secured to a bracket 36. This bracket is mounted on the ram 8 and reciprocates therewith. The roller 34 is mounted in a bearing 37. This bearing is secured to a stud 38 which is slidably mounted in a bracket 39. Interposed between the bearing 37 and bracket 39 is a coil spring 40 for resiliently holding the roller 34 in contact with the end 32 of the operating lever. The table 15 is also provided with a plurality of openings 41 which extend latterly across the table or between the ends of the strips 16. The purpose of these openings is to permit the material removed from the ends of the bricks to pass therethrough and prevent the lodging of these particles on the table and interfering with the passage of the bricks between the strips 16 and 17.

Secured to each leg of the U-shaped frames 27 are cutting or end scoring blades

42. These blades are for the purpose of scoring both ends of the bricks simultaneously.

The operation of my device is as follows:

5 After the machine has been assembled, the moulds 11 are charged with clay. The ram 8 is then driven downward, causing the plungers 10 to enter the moulds 11 and compress the material to form the brick. 10 The ram is then raised and the bricks forced upward out of the moulds by means of a movable bottom in the mould not shown as this part of the mechanism is old and present in all brick presses of a similar 15 nature. This leaves a brick with vertically extending ribs on both ends and one side. The plunger 13 then moves forward—the ram having previously ascended, and pushes the formed bricks between the strips 20 16 and 17, where the cutting edges 19 form horizontally extending cuts across the vertical ribs. During this movement the plunger 13 also charges the moulds for the next brick. Upon the descent of the 25 plunger, the roller 33 forces the operating lever into the position indicated by dotted lines in Fig. 1. This movement drives the U-shaped frames 27 across the ends of the bricks, and the cutters or end scoring blades 30 42 cut horizontal grooves across the ends of the bricks. Upon rising again the roller 34 operates on the operating lever and forces the ends scoring cutters to their original 35 position. The plunger 13 again comes forward, carrying with it the newly formed bricks. These bricks force the bricks previously acted on out from between the strips 16 and 17 on to the forward portion of the table where they are removed. 40 By this construction it will be seen that the operation of my device is entirely automatic and mechanical, and the finishing of the brick is done simultaneous with the pressing of a new brick so that no time is 45 lost nor is it necessary to slow down the machine which has been the trouble where a hand operated device for scoring the bricks is used.

In fact, by the use of my device the speed 50 of the machine is only limited by the rate of speed at which the finished bricks can be handled from the press to the kiln, and the timing of the various parts are all controlled from one roller and not dependent 55 on manual labor for operating any part thereof.

While I have shown my device as attached to a machine for making two bricks simultaneous, it is obvious that by a mere

duplication of the various scoring cutters 60 and moulds that the device can also be applied to presses turning out four, six, or more bricks at one operation, but regardless of the number of bricks made at one operation, only one lever for operating the 65 end scoring cutters is necessary.

Having fully described my invention, what I claim is:

1. A brick surfacing machine comprising a brick press having a ram, a table secured to said press, strips secured to said table, cutters secured in one of said strips and extending therefrom, a movable end scoring blade adapted to be moved across the ends of a brick by the downward movement of the ram. 70

2. A brick surfacing machine comprising a brick press having a ram, a table secured to said press, strips secured to said table, cutters located in some of said strips 80 and projecting therefrom, end scoring blades slidably secured to said table, and a lever for operating said end scoring blades across the end of a brick by the downward movement of the ram. 85

3. The brick surfacing machine of claim 1, in which the ram is provided with rollers for operating the end scoring blades.

4. The brick surfacing machine of claim 2, in which the ram is provided with rollers for operating the end scoring blades. 90

5. A brick surfacing machine comprising a brick press having a ram, a table secured to said press, guide strips located on said table to permit the passage of bricks 95 there-between, some of said guide strips having scoring cutters projecting therefrom, means for feeding bricks through said guide strips and side scoring blades, end cutters slidably secured to said table, a lever for operating said end scoring blades, and means carried by the ram for operating said lever. 100

6. The brick surfacing machine of claim 5, in which the ram is provided with rollers projecting therefrom for operating said lever backward and forward during its upward and downward movement. 105

7. A brick surfacing machine comprising a table, guide strips secured to said table, cutters secured in one of said strips and projecting therefrom, and movable end scoring blades carried by the table for scoring the ends of a brick. 110

In testimony whereof, I have signed my name to this specification.

JACOB STOCKE, JR.
